UNITED STATES PATENT OFFICE.

ALPHONSE H. KURSHEEDT, OF NEW YORK, N. Y., ASSIGNOR TO KURSHEEDT MANUFACTURING CO., OF NEW YORK.

DESIGN FOR TRIMMING.

SPECIFICATION forming part of Design No. 35,124, dated September 17, 1901.

Application filed August 24, 1901. Serial No. 73,209. Term of patent 7 years.

To all whom it may concern:

Be it known that I, ALPHONSE H. KURSHEEDT, a citizen of the United States, residing at New York, in the county and State of New York, have invented and produced a new, useful, and original Design for Trimmings, of which the following is a specification, reference being had to the accompanying drawings, forming part thereof.

10 In the drawings, Figure 1 is a plan or face view of the trimming; and Fig. 2 is a sectional view thereof, showing the configuration of the ribs, tucks, or corrugations.

15 In the drawings, *a* is a trimming of a general strip form. Extending longitudinally of the trimming, in the middle thereof, is a rib, tuck, or corrugation *b* of a generally rounded form. Disposed at each side of the middle

tuck or corrugation is a series of ribs, tucks, or corrugations *c* of less width than the rib, 20 tuck, or corrugation *b*, which ribs, tucks, or corrugations are of a rounded form and are inclined laterally of the trimming. These series of ribs, tucks, or corrugations adjoin the ribs, tucks, or corrugations *d*, running 25 longitudinally of the fabric and of greater width than the ribs, tucks, or corrugations *c*. These ribs, tucks, or corrugations are of a generally rounded form.

What I claim is—

30 The design for a trimming substantially as herein shown and described.

A. H. KURSHEEDT.
